UNITED STATES PATENT OFFICE.

DONALD BARNS MORISON, OF HARTLEPOOL, ENGLAND.

STEAM-CONDENSING AND VACUUM-PRODUCING APPARATUS.

1,085,152.

Specification of Letters Patent.

Patented Jan. 27, 1914.

Application filed December 18, 1912. Serial No. 737,464.

To all whom it may concern:

Be it known that I, DONALD BARNS MORISON, a subject of the King of Great Britain and Ireland, residing at Hartlepool, in the county of Durham, England, have invented Improvements in and Relating to Steam-Condensing and Vacuum-Producing Apparatus, of which the following is a specification.

10 This invention relates to improvements in steam condensing plant wherein air is primarily withdrawn from a condenser by a steam jet and discharged to the atmosphere by an expelling device. In such apparatus 15 wherein steam which has previously done work in an engine, as for example the exhaust steam from an auxiliary engine, is supplied to the steam jet withdrawing air from the condenser, the exhaust steam available is often variable in pressure and in 20 quantity, and often greater in amount than is required by the steam jet.

The object of this invention is to increase the efficiency of such apparatus, and for this 25 purpose a supply of steam is taken preferentially from the auxiliary exhaust system and delivered to the steam jet withdrawing air from the condenser, and when the steam is greater in quantity than can be utilized 30 in the steam jet and a predetermined pressure is reached, the remainder of the steam or such a proportion of it as may be convenient and practicable, is utilized for heating purposes as for heating feed water, or 35 alternatively, or concurrently, admitted to the low pressure section of a steam turbine so that of the total heat in the exhaust steam the whole, or as much of it as is practically convenient, is utilized beneficially.

40 In one form of my invention wherein exhaust steam from an auxiliary exhaust steam system or from an auxiliary exhaust steam pipe is utilized in a steam jet for withdrawing air from a condenser and which is therefore 45 after expelled to the atmosphere by air discharging means, I connect to the auxiliary exhaust steam system or to the auxiliary exhaust steam pipe, a valve which is so arranged that when the quantity of exhaust 50 steam is in excess of that which is supplied to the steam jet, such excess is utilized to heat water in a tank or vessel into which

water of condensation or water intended for boiler feeding purposes is discharged. The tank or vessel may be in the form of a direct contact heater to which the feed water is delivered, as for example, directly by a pump, or it may be by a pump which also delivers water to an air discharging device which expels to the atmosphere the air withdrawn by the steam jet.

When in sufficient quantity to justify its use for power production, any exhaust steam which is not utilized in the steam jet for withdrawing air from the condenser, may 65 pass through a suitable valve and be utilized in the low pressure section of a steam turbine as hereinbefore referred to, or the steam not used in the steam jet may be preferentially supplied to a water heating device 70 and means provided whereby when the steam is greater in quantity than can be utilized in the steam jet and for heating water, it passes into the low pressure side of a steam turbine, or when such an arrangement is undesirable, it may be discharged into the condenser or elsewhere as 75 required.

The accompanying illustrative drawings show more or less diagrammatically various 80 forms of apparatus according to the present invention.

In Figure 1, *a* is a condenser from which air is primarily withdrawn by a steam jet device *b* which receives a preferential supply 85 of steam through the pipe *m* from the exhaust *n* of the auxiliary turbine *c* that drives the pump *h* delivering water under pressure to the water jet nozzles in the water jet ejector *e* by which the air withdrawn from 90 the condenser by the steam jet is discharged to the atmosphere. The exhaust pipe *n* from the turbine *c* is also connected to the spring loaded valve *d* which is so arranged that when the steam is greater in quantity 95 than can be used in the steam jet device *b* and a predetermined pressure is reached, the valve opens and steam passes through the pipe *g* and nozzle *l* into the compartment *f* of the tank *p* in which it is condensed 100 by feed water therein.

In Fig. 2, the auxiliary exhaust steam, as in the previous arrangement, is preferentially supplied to the steam jet device *b*, and

when it is greater in amount than can be utilized in the steam jet for withdrawing air from the condenser *a*, the pressure in the exhaust system rises until a predetermined limit is reached when the valve *v*, which is of suitable construction, opens and steam passes through the pipe *u* into the low pressure section of the turbine *w*. In this example, the water of condensation is discharged from the condenser into the tank *p* by the rotary pumps *x*.

Fig. 3 is a modification of the arrangement shown in Fig. 2, in which the water of condensation is withdrawn from the condenser by a pump *x* that discharges into the suction pipe of the air pump *y* in which the air withdrawn from the condenser by the steam jet device *b* is expelled by water discharged from the periphery of a rotary device and is delivered together with the water of condensation from the pump *x* into the tank *p*. Exhaust steam from auxiliary machinery is delivered into the pipe *n* and is preferentially supplied to the steam jet device *b*, but when in greater quantity than can be utilized therein it passes through the valve *d* and nozzle *l*¹ into the heating compartment *f* of the tank *p* wherein it is used for heating the feed water which is thereafter withdrawn through the pipe *z*. The auxiliary exhaust system is also connected by the valve *v* to the turbine *w* and by the valve *d*² to the condenser *a* the arrangement being such that when the steam not utilized in the steam jet is greater than that required for heating the feed water and a predetermined higher pressure is reached, it passes by the automatically operated valves *v* and *d*² into the turbine *w* or into the condenser *a* or it may be concurrently into both the turbine and the condenser. The pipe *g* connecting the auxiliary exhaust system with the heating compartment *f* may be provided with a valve *i* that is automatically controlled by a temperature regulating device *j* so that the supply of heating steam passing through the pipe *g* is controlled in accordance with the temperature of the feed water.

The tank in which the feed water is heated may be in the form of a closed vessel as shown in Fig. 4 wherein *k* is an elevated direct contact heater to which the water of condensation is delivered by the pump *x* and from which it is discharged to the boilers by the rotary feed pump *x*¹. Exhaust steam from the turbine *c* driving the pumps *x* and *x*¹ and also the pump *h* which circulates the water through the water jet ejecting device *e*, is preferentially supplied, together it may be with other auxiliary steam entering the system through the branch *n*¹, to the steam jet device *b*, and when the steam is greater in quantity than can be used in the steam

jet and the pressure rises, it passes through the pipe *g* and loaded valve *d* into the heater *k*. The pipe *g* may also be provided with a valve *d*² which is loaded to a higher pressure than the valve *d* and through which the steam escapes to the atmosphere when it is greater in quantity than can be beneficially utilized in the steam jet *b* and in the heater *k*. Make up feed water, may if desired be delivered into the tank *p* and discharged by the pump *h* to the heater *k* through a valve *v*¹ which is controlled by a float in the tank *p*.

Fig. 5 is another arrangement of my invention in which the pipe *g* is connected to a regulating valve *r* that is operated by a float *q* so that when the supply of water delivered to the compartment *f* is below the normal amount, or ceases, the steam supply to the heating nozzle *l*¹ is throttled or cut off. The same float *q* may also operate a feed water discharge valve *s* in the manner illustrated, whereby when the supply of feed water is variable in quantity the float automatically regulates the supply of steam to the heating nozzle *l*¹ concurrently with the regulation of the feed water discharged through the valve *s* from the tank, or the float may control the feed water discharge valve only. In this arrangement, as in Fig. 4, exhaust steam from the turbine *c* and from auxiliary machinery is preferentially supplied from the pipes *n* and *n*¹ to the steam jet device *b*, and when in greater quantity than can be used in the steam jet the pressure rises and steam passes through the valve *d* into the tank *f*. Should the steam passing through the pipe *g* be greater than that required to be condensed in the tank *f*, the pressure rises still farther and steam passes through the valve *d*¹ to the turbine *w*, through the valve *v* or into the condenser *a* through the valve *d*², or it may be into both the turbine and the condenser, a valve *d*³ being provided for the escape of steam to the atmosphere.

Figs. 6 and 7 show detail sectional views of another convenient form of the tank *p* illustrated in Figs. 1 to 5. Fig. 6 is a sectional elevation on the line C—C in Fig. 7, and Fig. 7 is a sectional plan, the upper view being a section on the far side of the tank *p* on the line A—A in Fig. 6 and the lower view being a section on the near side of the tank on the line B—B. The tank comprises the compartments 1, 2 and 3, the compartment 1 having a chamber 4 containing the water jet devices *e*, by which the air withdrawn from the condenser by the steam jet devices *b* is discharged to the atmosphere. The discharge of water from the chamber 4 flows through the ports 5 and sieves 6 into the lower portion of the compartment 1, from whence it is withdrawn through the pipe 7 by the pump supplying

water to the ejectors *e*, the excess of water, or the amount of water corresponding to the quantity of steam condensed in the condenser, flowing over the weir *8* and downwardly through the passage *9* and opening *10*, into the lower portion of the compartment *2* wherein it is heated and circulated by the nozzles *b* that are supplied with exhaust steam from auxiliary machinery together with the steam that is not utilized in the steam jet devices *b*. The heated water from the compartment *2* flows by way of the passage *11*, formed in the compartment *1*, into the compartment *3* from which the water is withdrawn by a feed pump through the pipe *z*. The compartment *3* contains a float *q* which operates a valve *12* that is connected to a feed tank by the pipe *16* and to the condenser by the pipe *17*, the arrangement being such that whenever the water level in the compartment *3* falls below a predetermined limit, water is automatically passed from the feed tank through the valve *12* to the condenser from which it is withdrawn by the water withdrawing pump or pumps which discharge through the pipe *14* into the chamber *4*. The compartment *1* is provided with overflow pipes *15*, so that should the sieve become fouled, the water will rise and overflow through the pipes *15* into the lower portion of the compartment.

What I claim is:—

1. In combination a multiple stage turbine, a steam condenser receiving exhaust steam therefrom, a steam ejector for withdrawing air from said condenser, a pipe for supplying exhaust steam to said ejector, branch pipe connections leading from said exhaust steam supply pipe to the low pressure section of the turbine, and a pressure controlled valve governing the admission of steam to said branch pipe.

2. In combination a multiple stage turbine, a steam condenser receiving exhaust steam therefrom, a steam ejector for withdrawing air from said condenser, a pipe for supplying exhaust steam to said ejector, a feed water heater, branch pipe connections leading from said exhaust steam pipe to said feed water heater and the low pressure section of the turbine, and pressure controlled means for governing the flow of steam through said branch pipe connections.

3. In combination a multiple stage turbine, a steam condenser receiving exhaust steam therefrom, a steam ejector for withdrawing air from said condenser, a pipe for supplying exhaust steam to said ejector, a feed water heater, branch pipe connections from said exhaust steam supply pipe to said feed water heater, the low pressure section of the turbine and the condenser, and pressure controlled means for controlling the passage of the exhaust steam through said

branch pipe connections, substantially as described.

4. In combination a condenser, a steam jet primarily withdrawing air therefrom, means for expelling such withdrawn air into the atmosphere, an auxiliary engine for driving said means, a pipe for conveying the exhaust steam from said auxiliary engine to the ejector, a branch pipe connected with said exhaust steam pipe, and a pressure controlled valve governing the passage of steam to said branch pipe.

5. In combination a steam condenser, a steam ejector for withdrawing the air therefrom, a feed water heater, and an exhaust steam supply pipe having branches connected with said ejector and said feedwater heater, and an automatic pressure controlled valve for admitting steam to said second device when the pressure of exhaust steam reaches a predetermined amount.

6. In combination a steam condenser, a steam ejector for withdrawing the air therefrom, a feed water heater, an exhaust steam supply pipe having branches connected with said ejector and said feed water heater, an automatic pressure controlled valve for admitting steam to said second device when the pressure of exhaust steam reaches a predetermined amount, a valve in the branch of said supply pipe leading to said feed water heater, and a float located within the tank and connected to said valve for controlling the passage of exhaust steam thereto.

7. In combination, a condenser, a steam ejector for withdrawing air therefrom, a feed water heater, an exhaust steam supply pipe having branches leading to said ejector and said feed water heater, a valve in said branch for controlling the admission of steam to the feed water heater, a float within the feed water heater for controlling the valve, a valve controlling the water outlet from said heater, and connections between the float and said last named valve.

8. In combination a condenser, a steam ejector for withdrawing air therefrom, a feed water heater, a supply pipe for exhaust steam, branches leading from said exhaust steam supply pipe to said ejector and said feed water heater, a valve for controlling the admission of exhaust steam to the feed water heater from said branch pipe, and a thermostat within the feed water heater and connected to said valve for operating the same.

9. In combination a steam condenser, an air ejector for primarily withdrawing air therefrom, a tank having a plurality of compartments, water jet means for expelling to the atmosphere the air withdrawn by said steam ejector, said water jet means communicating with one of the compartments of said tank, a steam engine for driving said water

jet means, an exhaust steam pipe for said steam engine having a branch leading to the steam ejector, and a branch leading to said water tank, and heating nozzles in one of the compartments of said tank receiving the steam from said second branch.

Signed at West Hartlepool, in the county

of Durham, England, this 3rd day of December 1912.
